UNITED STATES PATENT OFFICE.

ARTHUR ERNEST OXLEY, OF DIDSBURY, MANCHESTER, ENGLAND, ASSIGNOR OF ONE-HALF TO THE BRITISH COTTON INDUSTRY RESEARCH ASSOCIATION, OF DIDSBURY, ENGLAND, AND ONE-HALF TO PLATT BROTHERS AND COMPANY LIMITED, OF OLDHAM, ENGLAND.

REVOLVING FLAT CARDING ENGINE.

Application filed February 4, 1927, Serial No. 165,801, and in Great Britain February 18, 1926.

These improvements relate to revolving flat carding engines wherein a greatly reduced number of revolving flats are used in accordance with the system fully disclosed 5 in the prior Patent No. 1,567,541.

My invention is an improvement in or modification of the invention described in the said former Patent 1,567,541.

The object of the present invention is to 10 produce a much simpler card which, whilst being cheap to make, shall yet be equally efficient as compared with an ordinary revolving flat card with its full complement of flats, and shall occupy less over-all space than 15 an ordinary card, and be easier to work as regards setting, grinding, etc. For instance the number of setting points can be reduced to two or three.

According to my present improvements I 20 do not use two cleaning or combing mechanisms but only one, that is, a single cleaning or combing mechanism fed from an ordinary lap over a normal dish feed. By virtue of the greatly reduced number of flats 25 this dish feed can be arranged appreciably above the level of the centre of the main cylinder so as to carry the taker-in as close to the chain of flats as may be desirable in order that a back plate or sheet of ordinary narrow width, or even less than ordinary width, 30 can be used, so that the material is almost immediately subjected to the action of the flats and all practical difficulties as to the fitting of the back plate or sheet are over- 35 come. I use a lap roller on which the lap to be fed rests and the level of the lap centre is about on the same level as the rear of the chain of flats and this allows me to make provision for supporting an extra lap in the 40 frame-work of the card and almost immediately below the lap supplying the material to be acted upon. I use two sets of cross- 45 rails one in front of the extra lap and one below, or as found convenient, which with the elevated frame sides carrying the taker- 50 in secure greater lateral stability which is most desirable.

The attached drawings clearly illustrate 55 the improvements:

Fig. 1 being a side elevation.

Fig. 2 is a sectional elevation, and,

Fig. 3 a plan.

According to the construction of card il-

lustrated and which embodies my improvements, I use a main cylinder *a* which is smaller in diameter than usual, as for instance it may be 40". It might be considerably larger in diameter than 40" or it may even be less. The diameter of the ordinary or normal cylinder is about 50".

As in the Patent 1,567,541, I still use a considerably reduced number of flats, say about 45, some 13 of which are in working position on the cylinder, the flats being marked *b*.

Just below the level of the flats is the simple single cleaning or combing mechanism clearly illustrated consisting of lap roller *c* (over which the lap *C* is disposed), dish feed *d*, fluted roller *e* and taker-in *f*, the latter being for example about 9" in diameter;

but it may be greater or less. The shaft *C* for the lap *C* is disposed in vertical slots *C*² formed in brackets *C*³ carried by the machine frame.

Mote knives *g* are used and a dirt grid *g'* with the taker-in *f*, and the taker-in can be brought so close up to the flats as to allow of a very narrow back plate or sheet *h* being used, as is clearly illustrated, and such back plate or sheet may be even narrower than in the ordinary card.

By reason of the position of the simple cleaning and combing mechanism a considerably augmented space *i* for dirt and impurities results, the full depth from the dirt grid of the taker-in to the floor being available, thus reducing the liability of the fly and impurities driven out by the taker-in *f* being drawn or sucked back by air currents between the grid bar spaces.

A plain sheet *k* encloses a section of the main cylinder and may extend to the floor. Dirt grids *l* are located below the main cylinder and a doffer *m* of some 22" or more or less may be used. The side frames below the simple single elevated cleaning and combing device are shaped to form brackets *n*² and provided with slots *n*³ forming bearings to receive the lap rod *n'* of an extra lap *n* which can thus be located below the lap in use.

Two sets of crossrails are provided, the one set in front of the extra lap being marked *o*, and the set below *o'*.

The setting points may be two or three, as already mentioned, as against five in an ordinary card, this representing an important simplification.

The improved construction of card in-

volves some changes in the driving arrangements, and these changes are clearly illustrated. I show the fluted roller e of the elevated cleaning and combing mechanism 5 driven from the side shaft p by a short upright shaft p' having bevel gear, the upper bevel wheel driving the plate bevel e' on the fluted roller e . For the doffer drive, I am not able to drive direct by a strap onto the 10 pulley on the dandy lever, as is usual, and so I drive by a vertical belt q' from the pulley on the licker-in shaft to a pulley q suitably carried. Another pulley q^2 drives by a strap q^3 the pulley q^4 on the dandy lever, which pulley q^4 through the usual gear wheels actuates 15 the doffer m . The elevated licker-in is shown as driven by a crossed belt r from the main cylinder shaft.

The complete card including coiler can and 20 the full laps as illustrated occupies a longitudinal space of about 9'-5" as against an over-all longitudinal space of 10'-3" in the case of an ordinary standard card.

The entire combination results in the obtainment of a considerably simpler but 25 equally efficient and more compact card, at once cheaper, more stable, and one which in use reduces practical difficulties such as setting, grinding, etc. to a minimum. These advantages are combined with a considerably 30 augmented free space i for dirt, fly, droppings and impurities on the underside of the taker-in, that is, more space than now obtains on a standard carding engine.

35 I declare that what I claim is:—

1. In a revolving flat carding engine, the combination with a main cylinder and a chain of flats comparatively small in number disposed in cooperative relation to said main 40 cylinder, of a single cleaning and combing mechanism comprising a taker-in roll supported for rotation in contact with said cylinder above the horizontal center line there-

of, a horizontally extending plate disposed rearwardly in juxtaposition to said taker-in 45 roll, a fluted roller mounted for rotation above said plate adjacent to said taker-in roll, a lap roller mounted for rotation adjacent to the rear edge of said plate, a pair of slotted brackets disposed above said lap 50 roller, a completely formed lap mounted for rotation in said brackets in contact with said lap roller, a narrow back plate enclosing that portion of the main cylinder between the chain of flats and the taker-in roll, and driving mechanism for said cleaning and combing mechanism.

2. In a revolving flat carding engine, the combination with a main cylinder and a chain of flats comparatively small in number disposed in cooperative relation to said main cylinder, of a single cleaning and combing mechanism comprising a taker-in roll supported for rotation in contact with said cylinder above the horizontal center line 65 thereof, a horizontally extending plate disposed rearwardly in juxtaposition to said taker-in roller, a fluted roller mounted for rotation above said plate adjacent to said taker-in roller, a lap roller mounted for rotation 70 adjacent to the rear edge of said plate, a pair of slotted brackets disposed above said lap roller, a completely formed lap mounted for rotation in said brackets in contact with said lap roller, a narrow back plate enclosing that portion of the main cylinder between the chain of flats and the taker-in roll, a second pair of slotted brackets disposed at a lower 75 level than said first pair for supporting an extra lap, and bevel gear driving mechanism 80 from the side shaft of the card for driving the single cleaning and combing mechanism.

In testimony whereof I have signed my name to this specification.

ARTHUR ERNEST OXLEY.
